UNITED STATES PATENT OFFICE.

WILLIAM STANLEY, JR., OF ENGLEWOOD, NEW JERSEY.

THERMAL CUT-OUT.

SPECIFICATION forming part of Letters Patent No. 310,472, dated January 6, 1885.

Application filed December 5, 1882. Renewed July 8, 1884. (No model.)

To all whom it may concern:

Be it known that I, WILLIAM STANLEY, Jr., of Englewood, in the county of Bergen and State of New Jersey, have invented certain new and useful Improvements in Electric Cut-Outs; and I declare the following to be a clear and exact description of the invention, when read in connection with the accompanying drawings.

10 The object of my invention is to prevent the dangers arising from and the loss of energy incident to overloading the conductor of an electric current, and this whether by a sudden increase in the current or by lessening the 15 resistance of the conductor, or by reason of cross-circuiting, or for any other cause; and my invention consists of an air-chamber so arranged in proximity to or surrounding an electric conductor that the heat generated in 20 the conductor by reason of an abnormal current shall effect a rupture of the conductor by expanding the air in the air-chamber, and thereby displacing a movable body arranged to close such chamber, and connected with or 25 constituting a part of such conductor.

In the drawings, Figure I is a perspective view of one form of cut-out embodying my improvements. Fig. II is a detail central section of the same, and Figs. III and IV represent 30 modifications thereof.

A is a tube, preferably, but not necessarily, of glass, which is closed at each end in any convenient way—in the present case by blocks B, which also support it in proper position 35 upon a wall, base, or bracket, C—and it is provided with a capillary passage, A', which unites the air-chamber A² with the receiving-chamber A³. Terminating in the air-chamber are two wires, D D', which constitute the 40 conductor of an electric current. One of these wires, D', enters the air-chamber through the capillary passage, without filling it, however, and its end and the end of the wire D are so arranged that a globule of mercury, E, too 45 large to pass through the capillary passage by reason of its own weight serves to unite them and complete the circuit D D'. The electric circuit within the air-chamber consists, in whole or in part, of material of lower conducting-power, and therefore is of greater resistance, than the portions of the circuit ex-

terior to the air-chamber; but it has such a degree of conductivity as to readily allow the passage of the current designed for this circuit; hence the operation of the apparatus 55 under the influence of abnormal conditions is this: An excess of current produces heat in that part of the conductor which is of low conductivity, and the heat thus generated expands the air in the air-chamber and forces 60 the globule of mercury which connects the terminals D and D' into the receiver below, thus breaking the overloaded conductor. The chamber A³, which receives the mercury when it is expelled from the air-chamber, may be 65 closed; but it is usually provided with a small opening, which will permit the air to enter or pass out. The air-chamber, however, should be practically air-tight, or at least to such an extent that the expansive action of the confined 70 air may be utilized for the purpose described. To re-establish the continuity of the conductor after it has been ruptured, as explained, the mercury has but to be agitated, with the lower chamber, A³, uppermost, when it will flow 75 back into the air-chamber, and, the air-chamber being placed in the position shown, it will again unite the terminals of the conductor.

In Fig. III, I show substantially the same device as is illustrated by Fig. I, the only change 80 being that the wire D' enters the air-chamber in the same manner as the wire D, instead of through the capillary passage.

It is manifest that the mercury or other liquid which is used to close the air-chamber, 85 and which is displaced by the expanding of the confined air, may be made to effect the rupture of the conductor in other ways than by being, as a movable part thereof, thrown out of contact with a fixed part, and the air-chamber, instead of containing, might be surrounded by, coils of that part of the conductor intended to be especially sensitive to changes 90 in the current.

I show in Fig. IV a modification of this character, in which the air-chamber G is supported upon pivots g, and is surrounded by a helix, H, arranged in the electric circuit which the device is intended to guard. Heat generated in this helix will, by expanding the air 95 contained in the chamber G, expel the mercury I therefrom, and cause this chamber to 100

rock on its bearings and break the electric conductor at *J*, one of the contacts at this point being of the requisite elasticity to permit the bulb *G'* to descend. So, also, a movable body of other material than mercury may be used to close the air-chamber, and may be connected with the conductor by means which shall produce a break in the conductor when the movable body is displaced by the expansion of the confined air.

That portion of the conductor which is within close proximity to or contained in the air-chamber may, as indicated, consist of material of relatively poorer conductive power than the rest of the conductor—such, for instance, as platinum; but a reduction of the conductor in cross-section will effect the same condition, which is, however, not essential to the successful operation of the apparatus.

20 What I claim as new is—

1. In an electric cut-out, the combination of an air-chamber, an electric conductor ar-

ranged in such proximity to said chamber that heat generated by the current will materially expand the confined air, and a movable body arranged to close said chamber and connecting with said conductor, as and for the purpose set forth.

2. In an electric cut-out, an air-chamber provided with a capillary passage normally closed by a liquid conductor, in combination with an electric circuit arranged in such proximity to said chamber that heat generated by the current will materially expand the confined air, as and for the purpose set forth.

3. In an electric cut-out, an electric conductor composed of two parts of different conductivity, in combination with an air-chamber closed by a movable body, substantially as and for the purpose set forth.
